UNITED STATES PATENT OFFICE.

ALLEN I. MERCER, OF MANNINGTON, WEST VIRGINIA.

MUSIC-LEAF TURNER.

No. 880,032.

Specification of Letters Patent.

Patented Feb. 25, 1908.

Application filed May 16, 1907. Serial No. 373,999.

To all whom it may concern:

Be it known that I, ALLEN I. MERCER, citizen of the United States, residing at Mannington, in the county of Marion and State of West Virginia, have invented certain new and useful Improvements in Music-Leaf Turners, of which the following is a specification:

This invention has for its object a simple, durable and efficient construction of music leaf turner by which the pages of a music book or other musical composition may be quickly turned in succession at the proper time and with precision, and the invention 15 consists in certain constructions, arrangements and combinations of the parts that I shall hereinafter fully describe and claim.

For a full understanding of the invention and the merits thereof and also to acquire a 20 knowledge of the details of construction and the means for effecting the result, reference is to be had to the following description and accompanying drawings, in which:

Figure 1 is a perspective view of my improved music leaf turner. Fig. 2 is a top plan view of the supporting case, the shaft being shown in section. Fig. 3 is a vertical sectional view of the device. Fig. 4 is a side elevation, the upper portion of the device 30 being broken away. Fig. 5 is a horizontal sectional view on the line y—y of Fig. 3.

Corresponding and like parts are referred to in the following description and indicated in all the views of the drawings by the 35 same reference characters.

The support of my improved music leaf turner comprises a case 1 which may be secured to any desired stand or to musical instruments by any suitable clamps, so that 40 the device may be easily attached or removed. Within the case 1 a toothed segment 2 is mounted, said segment being actuated in one direction by means of a spring 3 and being provided with a handle 4 which 45 projects forwardly out of the open side of the case, within convenient reach of the operator. A stop pin 4^a is mounted within the case and is adapted to abut against the handle 4 when the segment is turned in one direction, and against the body portion of the segment when the latter is turned in the opposite direction, so as to limit the movements of said segment. The segment 2 meshes 50 with a pinion 5 secured fast on a vertically extending shaft 6 journaled at its lower end in the case 1. A plurality of telescoping

tubes are mounted to turn and slide loosely on the said shaft 6, three of said tubes being shown in the present instance, designated 7, 8 and 9, although it is to be understood that my invention is not limited to any number. The outermost tube 9 is provided with a bayonet slot 10, the vertical portion of which opens downwardly at the lower end of the tube, and the next inner tube 8 is similarly provided at its lower edge with a bayonet slot 11. The shaft 6 is provided near its lower end with a radially extending pin 12 adapted to describe the arc of a circle, as the shaft is rotated, and coming to rest at one limit of movement of the shaft over a shoulder 12^a which is in the form of a ledge or upwardly projecting plate secured in proximity to the base of the shaft on the top plate of the case 1. The outermost tube 9 rests upon said shoulder in elevated position, when the parts are in readiness for operation. Each of the said tubes 7, 8 and 9 is provided with an outwardly projecting stud 13, and arms 14 are pivotally connected at one end to the respective studs of the tubes, said arms being preferably extensible, as clearly illustrated in the drawing. The joint between the stud and the arm is arranged so that the arm may be dropped down against the tube so as to occupy a minimum amount of space when the device is not being used. Each of the arms 14 carries a clip 15 of any desired type or formation, the said clips being adapted to be secured to the edges of the respective leaves of the book or musical composition, so as to turn the leaves when the arms are swung around in a manner now to be set forth.

In the practical operation of my improved music leaf turner, it is to be understood that at the outset the outermost tube 9 rests in an elevated position upon the shoulder 12^a and that the inner tubes 7 and 8 rest in successive and at still higher elevations with their studs supporting them by extending over the next outermost tube. Hence the bayonet slot of the inner tube or tubes will be held above or out of alignment with the bayonet slot of the next outer tube. As the segment 2 is then actuated by the operator, the pin 12 will enter the bayonet slot of the outermost tube and by engaging the tube will revolve the same until the said vertical portion of the slot comes into registry with the shoulder 12^a, whereupon the said tube will drop down upon the opposite sides of

said shoulder. This will manifestly effect the turning over of one leaf. The handle of the toothed segment will then be released and the spring 3 will draw the pin back to 5 initial position, whereupon said pin will enter the vertical portion of the bayonet slot of the next tube and repeat the operation. The innermost tube can dispense with a bayonet slot, but in lieu thereof it must be 10 provided with a projection or shoulder such as indicated at 16, so that it may be engaged by the tube.

From the foregoing description in connection with the accompanying drawings, it will 15 be seen that I have provided a very simple and efficient construction of music leaf turner in which the telescoping tubes are so arranged as to be expeditiously operated and with precision at every actuation of the 20 toothed segment 2. In order to set the device, the pin 12 will be held over and in alignment with the shoulder 12^a, so that the tubes may be raised and turned back and their 25 several arms engaged with the leaves of the book or sheet of music.

Having thus described the invention, what is claimed as new is:

1. A music leaf turner, comprising a support, a vertical shaft journaled on said support, 30 means for turning said shaft, said shaft being provided with a pin, and the support being provided with an upwardly extending shoulder with which said pin is adapted to register upon the rotation of the shaft, a plurality 35 of telescoping tubes loosely mounted on said shaft, said tubes being provided in their lower edges with bayonet slots with which said pin is adapted to successively engage so as to turn the tubes in succession, the tubes being adapted to drop one 40 after the other over the shoulder, and arms carried by the respective tubes, said arms being each provided with means for attaching it to a leaf.

45 2. A music leaf turner, comprising a support, a vertically extending shaft journaled on said support and provided with a radially extending pin, means for turning said shaft back and forth on the support, the support 50 being provided with a shoulder with which said pin is adapted to register upon the actuation of the shaft, a plurality of telescoping tubes loosely mounted to move vertically and revolve on said shaft, said tubes being 55 provided in the lower edges with downwardly opening bayonet slots adapted to successively pass down over the shoulder and also adapted to be successively engaged by the pin so as to carry them around towards the

shoulder, said tubes being provided at their 60 upper face with studs, and the stud of one tube extending over the upper edge of the next outermost tube and adapted to hold its tube at a higher elevation than the said next outermost tube, whereby the bayonet slots 65 of the several tubes will be normally out of alignment, and arms carried by the respective tubes, said arms being provided with means for attaching them to the leaves.

3. A music leaf turner, comprising a support, 70 a vertical shaft journaled on said support, means for turning said shaft, said shaft being provided with a pin, and the support being provided with an upwardly extending shoulder with which said pin is adapted to register 75 upon the rotation of the shaft, a plurality of telescoping tubes loosely mounted on said shaft, said tubes being provided in their lower edges with bayonet slots with which said pin is adapted to successively engage so as to 80 turn the tube in succession, the tubes being adapted to drop one after the other over the shoulder, and arms carried by the respective tubes, said arms being each provided with means for attaching it to a leaf, said arms 85 having a jointed connection with the tubes, whereby they may be folded against the same.

4. A music leaf turner, comprising a supporting case, a toothed segment mounted in said case and spring pressed in one direction, a pinion with which said segment meshes, a vertically extending shaft journaled in said case and to which said pinion is secured, said shaft being provided with a radially extending pin near its lower end, the case being provided with an upwardly extending shoulder with which said pin is adapted to register, a plurality of telescoping tubes loosely mounted on said shaft to slide vertically and turn 90 thereon, the several tubes being provided at their lower edges with downwardly opening bayonet slots, and adapted to be successively engaged by said pin so as to move the tubes in succession until their slots register with the 95 said shoulder, whereby the tubes in succession may drop over the shoulder, and arms carried by the respective tubes, said arms being provided with means for attaching them to the several leaves of a music book or the 100 like.

In testimony whereof I affix my signature in presence of two witnesses.

ALLEN I. MERCER. [I. s.]
